UNITED STATES PATENT OFFICE.

JOHN W. SLIEMERS, OF ST. JOSEPH, TENNESSEE.

STOVEPIPE-JOINT.

1,163,958.

Specification of Letters Patent.

Patented Dec. 14, 1915.

Application filed March 8, 1915. Serial No. 12,876.

To all whom it may concern:

Be it known that I, JOHN W. SLIEMERS, a citizen of the United States, residing at St. Joseph, in the county of Lawrence and State of Tennessee, have invented a new and useful Stovepipe-Joint, of which the following is a specification.

The present invention appertains to stove pipe joints, and aims to provide a novel and improved means for rigidly securing together the adjacent or telescoping ends of two stove pipe sections, whereby they will be held in alinement, and will be prevented from accidentally separating or from moving together or toward one another excessively, although the joint is such that a person may readily assemble and detach the pipe sections.

It is also the object of the invention to provide a pipe joint of simple and inexpensive nature, which will eliminate the use of extraneous securing elements, outside the pipe sections themselves, and whereby the joint will be a substantial one, will not be encumbering in construction, and will serve its office in a thoroughly efficient and practical manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein—

Figure 1 is a side elevation of the adjacent ends of two stove pipe sections in separated condition. Fig. 2 is an elevation of the pipe sections assembled. Fig. 3 is a longitudinal sectional detail taken on the line 3—3 of Fig. 2. Fig. 4 is a view similar to Fig. 3 illustrating a modification. Fig. 5 is a view similar to Fig. 1 illustrating another variation. Fig. 6 is a view similar to Fig. 2, illustrating the pipe sections of Fig. 5 assembled.

Referring to Figs. 1, 2 and 3, the co-operating pipe sections are designated by the numerals 1 and 2, the end of the section 1 being adapted to telescope or slip into the end of the outer section 2.

In carrying out the invention, the inner

section 1 is provided adjacent its end, with a transverse slit 3 of suitable length, and which is provided between and spaced from its ends with a curved or arcuate portion 4 projecting toward the end of the section, and forming a flexible tab 5 projecting toward the said end of the pipe section. The adjacent or co-operating end of the other section 2 is provided with a pair of V-shaped cuts 6 or notches 6, providing a tapered longitudinally-projecting flexible or bendable tongue 7 therebetween.

It will be evident that the interengaging portions of the pipes formed by the slit 3 and cuts 6, may be readily and inexpensively provided in old as well as new pipe sections, so that the pipe sections may be effectively locked together.

In assembling the pipe sections, they are telescoped together in the usual manner, and the tab 5 is lifted or flexed outwardly in any suitable manner, so that the tongue 7 may pass under the same through the slit 3 when the pipe sections are assembled. The tab 5 will then overlap the basal portion of the tongue 7 upon the outer side of the pipe, while the tongue 7 will project inwardly, and may be bent back, as clearly illustrated in Fig. 3, to prevent the pipes from accidentally separating or becoming displaced relative to one another. The pipe sections 1 and 2 being moved together, will cause that edge portion of the section 1 formed by the slit 3, to bind between the oblique or inclined edges of the cuts or notches 6, to limit the movement of the pipe sections toward one another, and to assist in holding the pipe sections in position relative to one another.

The present joint will be effective to lock the pipe sections together, and serves its office in a thoroughly efficient, simple and practical manner. To separate the pipe sections, the tongue 7 is bent back, so that it may be drawn out of the slit 3 when the pipe sections are separated. The tab 5 facilitates the assemblage of the parts, since it may be swung or moved outwardly to receive the tongue 7 thereunder.

Fig. 4 illustrates a slight variation, since the position of the interlocking parts is reversed. Thus, the outer pipe section 1' is provided with the slit forming the tab 5'; and the inner pipe section 2' is provided with the tongue 7', the tab 5' being disposed within the pipe, and the tongue 7' passing outwardly and being bent back upon the

outer side of the pipe, to hold the parts together. Since this is a mere reversal of the parts illustrated in Figs. 1, 2 and 3, further description is not deemed necessary. Said 5 views illustrate that the lock may be used in either manner.

Figs. 5 and 6 illustrate another variation in the specific embodiment of the invention. The inner and outer pipe sections are designated by the reference characters 1^a and 2^a, respectively, and the pipe section 1^a is provided with the transverse slit 3^a adjacent its end and having the curved portion 4^a providing the tab 5^a, while the pipe section 15 2^a is provided with the V-shaped cuts or notches 6^a forming the tongue 7^a, the same as in the forms above described. The tab 5^a is flexible, the same as the tongue 7^a, whereby the tongue 7^a may pass through the slit 20 3^a when the pipe sections are assembled. In this form of the invention, however, the basal portion of the tongue 7^a is provided with a transverse open slot 8^a extending from the lower or inner end of one of the 25 cuts on notches 6^a, as clearly seen by reference to Fig. 5. This slot 8^a is of advantage in the assembling of the pipe sections, as will presently appear.

In assembling the pipe sections 1^a and 2^a, the tongue 7^a is slipped under the tab 5^a and through the slit 3^a, but the tongue 7^a need not be bent back or reflexed within the pipe, since it is only necessary to rotate the pipe sections relative to one another in the 35 proper direction so that the portion of the pipe section 1^a at the respective end of the slit 3^a will be received by the slot 8^a, to prevent the separation of the pipe sections, until the pipe sections are rotated back to 40 sealing position.

From the foregoing, taken in connection with the drawing, it is believed that the

advantages and attributes of the invention will be obvious to those familiar in the art, without further comment being necessary, 45 it being noted that the several forms of the invention have common and characteristic features due to the general and specific structural details.

Although the invention is illustrated and 50 described as being employed in a stove pipe joint, it will be understood that the securing means may be employed for securing other pipes and other objects of sheet form together. 55

Having thus described the invention, what is claimed as new is:

A pipe joint comprising a pair of pipe sections having ends telescoped together, one pipe section having a transverse slit adjacent its end and provided with a curved portion between and spaced from its ends and forming a flexible tab projecting toward the other pipe section, the terminals of said slit being in alinement and projecting beyond said tab in opposite directions, the last mentioned pipe section having a pair of V-shaped cuts in its end forming a tapered longitudinally-projecting tongue extending under said tab and through said slot, the basal portion of said tongue being wider than said tab whereby the edges of the tongue bind within the terminals of said slit between the ends of the slit and said tab, the tongue being engaged to the first 75 mentioned pipe section for holding the pipe sections against separation.

In testimony that I claim the foregoing as my own, I have hereto affixed my signature in the presence of two witnesses.

JOHN W. SLIEMERS.
